UNITED STATES PATENT OFFICE.

WHITTLESEY ADAMS DRAKE, OF PETROLEUM, OHIO, ASSIGNOR TO THE PENNSYLVANIA TANK CAR COMPANY, OF SHARON, PENNSYLVANIA, A CORPORATION OF OHIO.

OUTLET VALVE FOR TANK CARS.

Application filed January 7, 1920. Serial No. 349,954.

To all whom it may concern:

Be it known that I, WHITTLESEY A. DRAKE, a citizen of the United States, residing at Petroleum, in the county of Trumbull and State of Ohio, have invented certain new and useful Improvements in Outlet Valves for Tank Cars, of which the following is a specification, reference being had therein to the accompanying drawing.

10 This invention relates to improvements in outlet valves for tank cars, and it pertains to certain improvements in the valves that are placed at the bottom of the tank and operated from within a dome projecting from 15 the top of the tank.

One object of my present invention is to so construct the parts that the valve can be easily removed for the purpose of regrinding or replacement by a new valve, should 20 the valve seat become worn or damaged, without the necessity of putting the car out of service as is frequently the case under similar conditions with the present "winged" type of valve.

25 Another object of my present invention is to so locate the spring which holds the valve on its seat, that it is not affected by the vibration of the tank while in transit.

A further object of my invention is to 30 provide means located at the upper part of the valve case for regulating the tension of the spring against the valve through its stem.

Another object of my present invention is 35 to encase the valve rod throughout its length within the tank by a pipe-jacket, which extends from the spring adjusting bushing to the rod bracket at its upper end, whereby the valve-rod is protected against surging of 40 the contents of the tank, and whereby the protecting pipe-jacket also acts as a spreader between the valve casing and the valve rod bracket.

Another object of my present invention is 45 to provide the lower part of the valve casing with a suitable surrounding skirt which overhangs the outlet ports to overcome the eddy action of liquids when passing through the outlet ports during the process of unloading.

A further object is to so construct my improved valve that it can be applied to the present standard four or six inch outlet-leg

by counter-boring and threading the upper end of the leg to which the improved valve 55 casing is applied.

In the accompanying drawings—

Figure 1 is a longitudinal sectional view of my improved valve, showing a part of the tank to which it is applied.

Figure 2 is a sectional view of a part of the upper portion of the tank with its dome, and showing the upper portion of my improved construction.

My improved valve construction is particularly adapted to be used in connection with tanks for transporting oils, such as kerosene, gasoline, etc.

In the drawings, 1 indicates the tank and 2^a the dome projecting from the top thereof, 70 both of which are of the usual construction. Projecting from the bottom of the tank is the valve-leg 2, and this projects the regulated distance below the tank bottom. It is fastened to the tank in any desired manner, 75 but as here shown, it is secured by a suitable number of rivets 3.

In carrying out my improvement, I provide a valve casing A, which comprises a lower section 4 and an upper section 5. The 80 lower end of the section 4 has a reduced external screw-threaded projecting flange end 5', which meshes with an internally screw-threaded opening or recess 6 formed in the leg 2. This screw-threaded connection is 85 locked against becoming unscrewed by a suitable locking bolt or screw 7, which passes through the flange 5' and engages the wall of the screw-threaded recess. Above the flange 5' the section 4 is enlarged, as shown 90 at 8, and this enlargement projects into and above the bottom of the tank 1, and is provided with a suitable number of transversely arranged outlet ports 9. Below the outlet ports 9, the lower section 4 is provided 95 with a conical-shaped valve seat 10, with which a conical shaped valve 11 seats to make a liquid-tight closure. This valve 11 is preferably hollow and has a straight vertical portion 12, above its tapered valve portion which snugly fits against the straight vertical walled opening 13, and in which opening the valve is adapted to reciprocate vertically.

The upper section 5 of the case and the upper end of the lower section 4 are 100 provided with outwardly extending flanges

14 through which suitable bolts 15 pass, for the purpose of bolting the two parts together.

A valve operating rod 16 has its lower end 5 screwed into an upwardly extending projection 18 on the valve 11, and is held locked therein by a suitable lock nut 19 or cotter-pin 20 or both. This rod extends through the casing and up into the dome 2^a and 10 passes through a bracket 21 which extends inward from the wall of the dome 2^a, as clearly shown in Fig. 2. A screw-threaded bushing 22 passes through a screw-threaded opening 23 in the upper end of the section 15 5, and this bushing is provided with a suitable nut 24, by means of which it can be turned within the section 5, for the purpose of adjusting it up and down through the said section 5. Surrounding the lower end 20 of the valve rod 16 is a suitable spring 25, and the lower end of this spring abuts against the nut 19, and its upper end against a washer 26 placed between it and the lower end of the bushing 22. By adjusting the 25 bushing 22 downward, the tension of the spring 25 on the valve 11 may be regulated to cause a proper tight seating of the valve 11 with its seat 10, and the bushing is locked in its adjusted position by means of a lock-nut 27.

For the purpose of preventing eddies which occur in the liquid as it flows through its outlet-ports, I provide the section 4 of the valve casing with a depending bell-shaped skirt 28, which overhangs the outlet-ports 9. The formation of eddies interfere with the rapid outflow of the liquid and by means of this skirt an even and rapid outflow is obtained by preventing the 35 formation of these disturbing eddies in the outflowing liquid.

For the purpose of protecting the valve rod 26 from the surging of the liquid within the tank, and also for the purpose of providing a spreader between the upper end 45 of the adjustable bushing 22 and the bracket 21, I surround the valve rod with a protecting jacket 29 in the form of a pipe. The upper end of this jacket 29 is below and 50 supports the inner end of the bracket 21 and the lower part 30 of the jacket 29 is made in a separate section 30. The lower end of the part 29 of the jacket and the upper end of the part 30 are externally screw-threaded and are connected by a screw threaded nipple 31, by means of which the jacket may be elongated or shortened, for the purpose of properly adjusting its length 55 between the bracket 21 and the upper end 60 of the bushing 22.

The upper end of the valve rod 16, passes through the bracket 21 and extends there-beyond and is provided with suitable nuts 32 and 33. An operating lever 34 has its 65 inner end 35 surrounding the valve rod be-

tween the nuts 32 and 33 and bracket 21. The head 35 of this lever 34 is provided with a cam 36, whereby when the lever is turned, the cam engages the bracket 21 to lift the valve 11 from its seat.

By means of the valve constructed as described, the casing with its valve can be readily unscrewed from the leg 2, and removed from the tank for the purpose of regrinding the valve and its seat in a mechanical manner, which cannot be done with the construction of the valve originally used. This removal and regrinding of the valve when necessary is readily and quickly accomplished, thus not requiring that the car be out of service any appreciable length of time. Furthermore, the valve and its casing are readily and quickly removable, and a new one quickly substituted therefor and without throwing the car out of service any appreciable amount of time, which is not true with the form of valve now in use.

By placing the spring within the valve casing, I prevent it being affected by the vibration of the car in transit, whereby a constant steady downward tension is caused on the valve, and whereby an undisturbed seating of the valve is accomplished when the car is in transit, thereby preventing any leakage of the liquid through the valve.

A protecting jacket for the valve stem also prevents the surging contents of the tank from affecting the valve stem, which would have a tendency to vibrate the valve 100 on its seat and thereby cause leakage.

Again, my improved casing and its valve may be applied to the standard four or six inch outlet leg by counterboring and threading the upper end of the leg, as here shown, to receive the lower screw-threaded end 5' of the lower section of my improved valve casing.

Having thus described my invention, what I claim and desire to secure by Letters is—

1. The combination with a depending valve leg of a tank, of a valve casing connected with the valve leg, the casing having at its lower end an internal valve seat and laterally extending openings above the valve seat, a vertically movable valve within the casing, said casing having a surrounding skirt located immediately above the said openings and extending outwardly from the casing and larger in diameter than the casing to project beyond the said openings for the purpose of preventing eddies in the liquid flowing through the said openings.

2. The combination with a tank, of a valve casing having an outlet port and an internal valve controlling the port, a valve rod passing through the casing, an adjustable bushing surrounding the valve rod and

projecting into the case, an expanding spring between the valve and the inner end of the bushing, a bracket at the top of the tank through which the upper end of the valve rod passes, and an adjustable jacket surrounding the valve rod with its lower end engaging the upper end of the adjustable bushing and its upper end engaging the bracket, the parts arranged for the purpose described.

5 3. The combination with a tank having a dome at its top, of an outlet valve casing at its bottom, a vertically movable valve and

a spring depressing it located in said casing, a bracket extending from the wall of 15 the dome, a rod attached to the valve extending through the casing and to said bracket, a jacket surrounding the rod located between the bracket and the casing, and means engaging the bracket for lifting 20 the valve, whereby the rod jacket supports the end of the bracket under the lifting strain.

In testimony whereof I hereunto affix my signature.

WHITTLESEY ADAMS DRAKE.
